DISH RACK

Ralph C. Christophersen, 27 172nd St., Hammond, Ind.

Filed Feb. 10, 1961, Ser. No. 63,885

Term of patent 14 years

(Cl. D44—29)

FIG. 1 is a top plan view of a dish rack embodying my new design;

FIG. 2 is a bottom plan view thereof;

FIG. 3 is an end elevational view as seen from the bottom in FIG. 1;

FIG. 4 is an end elevational view as seen from the top in FIG. 2; and

FIG. 5 is a side elevational view as seen from the left hand side in FIG. 1.

I claim:

The ornamental design for a dish rack, substantially as shown.
